(57) **CLAIM**

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the interior of the solid lines and the unshaded areas within each form no part of the claimed design. The broken lines and unshaded areas depicting the remainder of the shoe form no part of the claimed design.

1 Claim, 3 Drawing SheetsFIG. 2

FIG. 3
